CASING FOR A WRITING INSTRUMENT

Harold E. Koeln, St. Louis, Mo., assignor to Penn
Corporation, Princeton, N.J.

Continuation of design applications Ser. No. 17,025 and
17,027, both filed May 6, 1969, both now abandoned.
This application June 1, 1970, Ser. No. 23,250

Term of patent 14 years

Int. Cl. D19—06
U.S. Cl. D74—17

FIG. 1

FIG. 2

FIG. 3

FIG. 4

FIG. 5

FIG. 6

FIG. 7

FIG. 8

FIG. 1 is a plan view of a casing for a writing instrument showing my new design;

FIG. 2 is another plan view thereof as it appears rotated 90° from FIG. 1;

FIG. 3 is an end view as seen from the left of FIG. 2;

FIG. 4 is an end view as seen from the right of FIG. 2;

FIG. 5 is a plan view of another embodiment of the casing for a writing instrument shown in FIG. 1 wherein the clip has been moved up on the cap portion;

FIG. 6 is another plan view thereof as it appears rotated 90° from FIG. 5;

FIG. 7 is an end view as seen from the left of FIG. 6; and

FIG. 8 is an end view as seen from the right of FIG. 6.

This application is a continuation of my applications Ser. No. D.17,025 filed May 6, 1969 and Ser. No. D.17,027 filed May 6, 1969 both now abandoned.

I claim:

The ornamental design for a casing for a writing instrument, as shown and described.
